CHARLES AUGUSTUS REIF AND ALLAN FRANK REIF, OF BUFFALO, NEW YORK.

OIL-FEED-CONTROL VALVE FOR OIL-BURNING APPARATUS.

Application filed March 8, 1926. Serial No. 93,283.

Our invention relates to improvements in oil feed control valves for oil burning apparatus, and the object of the invention is to construct an electrically actuated valve for controlling the supply of oil to the burner. A further object of the invention is to provide means whereby the flow of oil is stopped at a plurality of points when the valve is closed, and a still further object is to provide means whereby oil is always contained in the conduit of the valve mechanism when the valve is closed so as to preclude any possibility of air pockets being formed which might tend to restrict the flow of oil when the valve is opened. Another object of the invention is to devise means in the valve whereby the passage of oil is cut off at one or more points before the valve is completely closed so as to prevent any possibility of an oil flow should the valve through any unforeseen circumstances not move to the limit of this closed position when it is intended to do so, and another object of the invention is to wire the electrically actuating means for the valve in the same circuit as an electric motor operating the blower fan so that the actuation of the valve is in direct relation to the operation of the blower fan motor.

Our invention consists of an oil feed control valve for oil burning apparatus constructed and arranged all as hereinafter more particularly described and illustrated in the accompanying drawing in which:

Fig. 1 is a vertical sectional view taken through our valve, the electrical actuating means therefor being diagrammatically shown.

Fig. 2 is a reduced, elevational, diagrammatic view of the valve, blower fan and oil burning mechanism, showing the electrical connections between the valve and the blower fan motor, and,

Fig. 3 is a fragmentary sectional view showing a portion of our valve plunger and casing therefor, the plunger being shown at a point before reaching the limit of its movement in closing the valve.

Like characters of reference indicate the corresponding parts in the different views.

1 is the main portion of the valve casing being of substantially cylindrical form and containing a circular passage 2 which extends longitudinally therethrough, its lower end terminating in a valve seat 3 and communicating with a reduced longitudinal pas-

sage 4 which in turn communicates with a passage 5 of approximately the same diameter as the passage 2. The lower end of the casing 1 constituting the passage 5 is exteriorly threaded and adapted to receive a screw joint 6 of the usual type for connecting the oil inlet pipe 7 which communicates with the passage 5.

Upper and lower branch pipes 8 and 9 extend outwardly from the casing 1 intermediately of its length and having their outer ends exteriorly threaded for receiving the joint nuts 10 and 11 of a U-shaped pipe 12 which constitutes a connection between the two branch pipes 8 and 9. 13 is a third branch pipe extending from the valve casing 1 and is positioned diametrically opposite the branch pipe 8, its outer end being suitably connected to an oil conduit 14 which extends to the combustion chamber, feeding oil thereto in the usual manner. If it is desired to always maintain an oil supplied pilot light in the burner when our valve mechanism is closed we provide a conduit 15 leading from the passage 4 to the oil conduit 14, such conduit 15 is of course of a necessarily small bore so that only a small quantity of oil is supplied.

Our valve consists of a circular plunger 16 slidably positioned in the passage 2, a minimum clearance being left between the plunger and wall of the passage so as to prevent a flow of oil therearound. The lower end of the plunger 16 is reduced to constitute a needle valve member 17 which is adapted to enter a valve seating 18 constituted in the upper end of the passage 4, its lower tapered point 19 seating upon the tapered valve seat 20 when the plunger is in the closed position. 21 The shoulder 21 constituted between the needle valve 17 and the plunger is also adapted to seat upon the valve seating 3 when the plunger is in its closed position.

The upper end of the plunger 16 is adapted to project through the upper open end of the passage 2 in the casing 1 and is provided with an iron knob 22 the function of which will be hereinafter described. 23 is a diametrically positioned orifice extending through the plunger 16 intermediately of its length and adapted to register with the orifices in the oppositely positioned branch pipes 8 and 13 when the plunger is in its uppermost position for permitting the passage of oil from the U-shaped pipe 12 to the conduit 14. For preventing any rotative

movement of the plunger 16 which would permit the orifice 23 going out of alignment with the branch pipes 8 and 13 we provide the upwardly extending pins 24 upon the upper face of the valve casing 1 which are adapted to project into the orifices 25 in the lower face of the knob 22, the pins freely sliding in such orifices. For actuating the valve plunger 16 we provide an electromagnet 26 which is suitably positioned above the iron knob 22 and adapted to lift the said knob and plunger to open the valve when the magnet is energized. Upon the electromagnet 26 being demagnetized through the electric current being cut off the weight of the knob 22 will be sufficient to restore the plunger 16 to its lowermost or closed position.

The operation of our valve is as follows: Upon reference to Figure 1 of the drawing it will be seen that the valve is in the open position, that is, there is a direct communication for the oil from the oil supply pipe 7 through the passages 5, 4 and lower 25 portion of the passage 2 which in turn communicates with the branch pipe 9, U-shaped pipe 12 and branch pipe 8 leading back to the upper portion of the passage 2. As the plunger is in the uppermost position the 30 diametrical orifice 23 therein is constituting a communication between the branch pipes 8 and 13 and so permits the oil to flow to the oil conduit 14 leading to the combustion chamber of the burner. To lift the plunger 35 to this position the electromagnet 26 is energized attracting the knob 22 as before described. When the plunger 16 reaches its lowermost position the needle valve 17 will be seated in the valve seat 20 and the valve face constituted by the shoulder 21 between the plunger and the needle valve will be seated upon the valve seat 3; also the lower portion of the plunger 16 and the orifice 23 in its upper end will have passed the entrances to the branch pipes 9 and 8 respectively thus cutting off the passage of oil from the entrance passage 5 to the oil conduit 14 at four distinct points and thus reducing to a minimum any possibility of 50 leakage.

On reference to Figure 3 it will be seen that the plunger 16 is shown before it reaches the limit of its downward movement in closing the valve and it will be appreciated that at the point of travel shown although the needle valve has not been seated that the passage of oil through the valve is cut off as the entrance to the branch pipe 9 has been covered by the lower portion of the plunger 16 and the orifice 23 in the plunger has moved away from the branch pipes 8 and 13. It will also be seen that by closing the entrance to the branch pipe 9 before the valve 17 is closed and the oil supply cut off 65 from the lower portion of the passage 2 that

a means has been devised for insuring that the U-shaped pipe 12 is completely filled with oil as such oil therein is under pressure from the oil supply tank, not shown, until the moment that the entrance to the branch pipe is completely closed. By this provision any possibility of air pockets being formed in the valve conduits is obviated as even the orifice 23 in the plunger 16 has oil passing therethrough until the moment that it passes out of alignment with the branch pipes 8 and 13 and therefore is also full of oil when it is in the inoperative position.

When the plunger 16 reaches its lowermost position in closing the valve the needle valve 17 and valve face 21 will be completely seated upon the valve seats 20 and 3 respectively thus constituting further closures against the passage of oil so that the valve plunger 16 makes closure at four points, viz, 85 the needle valve 17 seated upon the valve seat 20, the valve face 21 seated upon the valve seat 3 and also the plunger itself closing the entrances to the branch pipes 9 and 13. When it is desired to permit the oil to 90 flow to the burner the magnet is energized attracting the iron knob 22 and lifting the plunger 2 into the open position as before described.

Upon reference to Figure 2 it will be seen 95 that when the electric circuit actuating the motor is cut off that the magnet will become immediately demagnetized permitting the knob 22 and plunger 2 to drop and closing the valve. When it is desired to start the burner it is merely necessary to switch on the electric current to start the blower fan motor when the electro-magnet 26 will become energized lifting the plunger 2 to the open position. By providing the pilot light 105 oil conduit 15 in the oil passage 4 it will be seen that a small quantity of oil will always be supplied for the pilot irrespective of whether the valve is closed or open.

From the above description it will be apparent that we have devised an extremely simply constructed oil flow control valve comprised of a minimum of parts which will cut off the flow of oil at a plurality of points and thus constitute an extremely effective 115 seal, furthermore by constructing our device so that some of the closures are prior to others we have devised means for preventing the oil draining out of the valve and air pockets being formed. By the provision of an electro-magnet for actuating the valve we have constructed a mechanism in which the operation of the valve is directly dependent upon the operation of the blower fan motor so that the possibility of any waste or overflow of oil due to the stoppage of the air supply to the burner is obviated.

What we claim as our invention is:—
1. A valve comprising a casing having a passageway with upper and lower spaced

apart orifices therein, a fluid conduit connecting said orifices, a fluid outlet conduit extending from the passageway in the valve casing, a plunger reciprocal in the passageway and having an orifice extending therethrough, means for moving said plunger for uncovering the lower orifice to permit fluid passing between the passageway and the fluid conduit, and means whereby the orifice extending through the plunger is caused to register with the upper orifice and the fluid outlet conduit to permit the flow of fluid therethrough.

2. A valve comprising a casing having a passageway therein and communicating with a second passageway, a valve seat constituted at the communicating point of the two passageways, a plunger reciprocal in the

first-mentioned passageway and having an orifice extending therethrough, a fluid conduit leading from the lower portion of the first-mentioned passageway to its upper end, a fluid outlet conduit extending from said passageway, said orifice extending through the plunger constituting a connection between the two fluid conduits when the plunger is in its uppermost position uncovering the lower entrance to the fluid conduit, and means whereby the downward movement of the plunger closing the valve causes the orifice extending through the plunger to come out of alignment with the fluid conduits before the lower end of the plunger is seated upon the valve seat.
